UNITED STATES PATENT OFFICE.

CHARLES N. BARTON, OF INDIANAPOLIS, INDIANA, ASSIGNOR OF ONE-FOURTH TO FRED N. REYNOLDS AND ONE-FOURTH TO FRED K. MURPHY, BOTH OF INDIANAPOLIS, INDIANA, AND ONE-TWELFTH TO EVELYN M. DINNIN, OF NEW YORK, N. Y., ONE-TWELFTH TO MARTHA E. DAVIS, AND ONE-TWELFTH TO MAY E. REYNOLDS, BOTH OF INDIANAPOLIS, INDIANA.

SECTIONAL JOURNAL BOX AND HUB LINER.

Continuation of application Serial No. 482,514, filed July 5, 1921. This application filed January 28, 1922. Serial No. 532,436.

To all whom it may concern:

Be it known that I, CHARLES N. BARTON, a citizen of the United States, residing at Indianapolis, in the county of Marion and 5 State of Indiana, have invented a new and useful Sectional Journal Box and Hub Liner, of which the following is a specification, reference being had to the accompanying drawings and to the letters and figures 10 of reference marked thereon.

This invention relates to liners for wheel hubs and journal boxes and is designed for the purpose of reducing lost motion of the journal boxes longitudinally on axles or 15 shafts, or of axles or shafts relatively to the journal boxes, especially in locomotives, the invention having reference more particularly to improvements in sectional journal box and hub liners of the character disclosed 20 in my application for Letters Patent filed July 5, 1921, Serial No. 482,514, of which this is a continuing application for Letters Patent.

An object of the invention is to provide 25 a liner of the above-mentioned character which shall be so constructed as to be adapted to be very securely and reliably held in place under the severe conditions of operation of locomotives, and which may be 30 readily applied to wheel hubs and journal boxes and be quickly and easily replaced when necessary.

Another object is to provide locomotive 35 wheel hubs and journal boxes with sectional liners which shall be so constructed as to be enabled to withstand the strains imposed upon them in operation by frictional contact with adjacent elements, and not jeopardize the devices whereby the sections of 40 the liners are connected together.

A further object is to provide an improved sectional hub or journal box liner including improved means for securing the liner in place on an axle or shaft so as to 45 not be liable to be broken or damaged in use, and which may be advantageously and inexpensively constructed and applied either to new machinery or to machinery in which lost motion may have developed in service, 50 which also shall be reliable, durable and economical in use.

With the above-mentioned and other objects in view, the invention consists in a liner holder or core having novel structural features, and a liner having also novel structural features whereby to removably lock it 55 securely to the holder or core, and the invention consists also further in the parts and combinations and arrangements of parts as hereinafter particularly described 60 and further set forth in the appended claims.

Referring to the drawings,—Figure 1 is an elevation of a locomotive wheel and axle, representing particularly the outer side of 65 a trailer wheel of a modern locomotive, the axle journal being on the outer side of the wheel as is preferred in some cases, the outer side of the hub of the wheel being provided with the improved liner as a sufficient 70 illustration of the purpose of the liner as a substitute for the worn away face of the hub which it is commonly known operates against a journal box on the axle journal; Fig. 2 is a sectional elevation of 75 the wheel and axle, the periphery or edge of the hub liner on the wheel being seen; Fig. 3 is a fragmentary section of the wheel hub on an enlarged scale, the holder or core of the liner being shown in central section 80 transversely with one section of the liner thereon; and, Fig. 4 is a front face view of the improved liner holder and the liner sections thereon, being partially broken away, the sections of the liner being separated as when about to be secured to the 85 holder or core.

In the different figures of the drawings, similar reference characters indicate corresponding or like elements or features of 90 construction herein referred to in detail.

In the drawings, the numeral 1 indicates the rim portion of a wheel, in some cases having a separate tire, the wheel having a hub 2 in which is a bore 3 receiving 95 an axle 4 having a journal 5 projecting beyond the outer face of the hub. The hub has a suitable number of bolt holes 6 extending from the outer face thereof, the holes being necessary to receive securing 100 bolts in case the holder or core of the liner is made separately from the hub and applied

thereto as is preferable. In case the bolt holes do not extend entirely through the hub they are screw-threaded.

A liner holder or core 7 is provided which 5 preferably is composed of sheet metal, such as heavy boiler plate, and each holder has a central aperture 8 through which the axle extends, the plate being arranged against the outer or wearing face of the 10 wheel hub. The holder may obviously be composed of two or more parts, if desired, to permit it to be placed on an axle in case the axle journal is on the inner side of the wheel, or to permit the holder to be placed 15 on the axle when not convenient to place it over the end of the axle or journal. The holder plate has a suitable number of bolt holes 9 therein that receive bolts 10 inserted in the bolt holes 6 whereby the holder is 20 firmly secured to the hub. The holder has a cylindrical peripheral portion 11 at its rear side from which a peripheral rib 12 extends adjacent to the front side of the holder. The rib has a suitable number of 25 lugs 13, 14, 15 projecting therefrom, on one side of the axis of rotation, and similar lugs 13', 14' and 15' on the opposite side. The lugs 13 and 13' are diametrically opposite each to the other as are the remaining lugs 30 similarly indicated. The holders are made rights and lefts and designed to be applied so as to be most efficient when rotating in the direction resulting from forward movement of the locomotive. To this end the 35 ends of the lugs are shaped so as to approximate the forward and rearward edges of saw teeth; but in order to be enabled to apply the liner sections to the holder closely without lost motion the ends of the lugs on 40 one side of the holder differ each from the other; so that the forward ends 16 and 16' each correspond approximately to a radial line, the rearward ends 17 and 17' of the lugs 13 and 13' respectively being inclined 45 or beveled and preferably curved slightly so that the end is convex. The lugs 14 and 14' have concavely curved undercut forward ends 18 and 18' respectively and sloping convexly curved rearward ends 19 and 50 19' respectively, the inclination of the ends relatively to radial lines being greater than the rearward ends of the first-mentioned lugs. The lugs 15 and 15' have undercut 55 concavely curved forward ends 20 and 20' respectively and convexly curved sloped rearward ends 21 and 21' respectively, the inclination of the ends relatively to radial lines being greater than that of the adjacent lugs. 60 The wearing parts of each liner designed to be renewed comprises two segmental sections having semi-circular face plates 22 and 22' respectively that are arranged together on the front of the holder or core 7, 65 and they have lateral rim portions 23 and 23'

respectively that embrace the peripheral rib 12, the remaining portions having lips 24 and 24' respectively that engage the rear side of the rib. The rim portion of one of the liner sections has slots 25, 26 and 27 70 therein to receive lugs 13, 14 and 15 respectively, the companion section likewise having slots 25', 26' and 27' to receive the remaining lugs respectively. The ends 28 and 29 of the slot 15 correspond in contour 75 to the ends of the lug 13, the ends 30 and 31 of the slot 26 corresponding to the ends 18 and 19 respectively of the lug 14, the ends 32 and 33 of the slot 27 corresponding to the ends 20 and 21 respectively of the lug 80 15. Likewise the slot 25' has ends 28' and 29' corresponding to the ends of the lug 13', the slot 26' having ends 30' and 31' corresponding to the ends of the lug 14', the slot 27' having ends 32' and 33' corresponding to the ends of the lug 15'. The curvature of the ends of the lugs and the slots correspond to the curvature of circles whose centers are approximately at two points 34 and 34' on diametrically opposite 90 portions of the periphery of the rib 12, in order that the sections may be easily turned about said points to swing them onto or from the holder or core and permit the slots to receive the lugs in close fitting arrangement. The two sections are identically alike and therefore interchangeable, the lugs on the holder being spaced apart accordingly. 95

The two sections may be variously secured together on the holder, but preferably are 100 bolted together, one section having ears 35 and 36 at its opposite ends, the other section having similar ears 35' and 36' on its ends respectively, one of the ears on each section having preferably a screw-threaded 105 bolt hole 37 and the other ear a smooth bolt hole 38, permitting bolts 39 and 39' to be turned in the smooth holes and screwed into the threaded holes, lock nuts 40 and 40' being placed on the bolts as safeguards 110 against the bolts becoming loose.

It should be understood that larger sizes of liners for use on driving wheel hubs and driving boxes may be provided with a relatively larger number of lugs and slots than 115 indicated, and in some there may be a smaller number.

While the preferred structure has the particular lug contours above described it should be understood that fairly good results may be obtained by means of lugs having other contours, as for instance, the ends of the lugs may all be straight and parallel each to the other, permitting the liner sections to be moved squarely each 120 towards the other when applying them to the core.

In practical use the plates 22 and 22' of the sections wear away, the side friction thereon having a tendency to turn the liner 125 130

on its holder or core, but the tendency is resisted by the gripping actions of the lugs on the holder which tend to draw the sections inwards to the holder, this being an 5 advantage especially in case one or both of the securing bolts become loose or lost. In case of loss of both securing bolts the sections of the liner may be retained on the core until rotation ceases, when one or both of the 10 sections might fall from place with no serious results. When a liner has become worn away until it is practically useless the sections are readily disconnected from the core and new sections applied as before to the 15 holders or cores.

Having thus described the invention, what is claimed as new is:—

1. A sectional journal box and hub liner having an annular holder provided on its 20 outer edge with a plurality of projecting lugs, and a plurality of segmental sections having slots receiving the lugs and provided with means to secure the sections together.

2. A sectional journal box and hub liner 25 having an annular holder provided with peripheral lugs projecting circumferentially in one direction, and a plurality of segmental liner sections having slots corresponding to and receiving the lugs and provided with 30 means to secure the sections together on the holder.

3. A sectional journal box and hub liner having an annular holder provided on its outer edge with lugs having undercut ends 35 and opposite sloping ends, and a plurality of segmental liner sections having slots corresponding to and receiving the lugs and provided with means to detachably secure the sections together on the holder.

40 4. A sectional journal box and hub liner having an annular holder provided on its outer edge with a plurality of projecting lugs circumferentially inclined in one and the same direction, two of the lugs being diametrically opposite each to the other and inclined more than others of the lugs, a plurality of segmental sections having slots inclined correspondingly to and receiving the lugs, and means for securing the sections 45 together.

50 5. A sectional journal box and hub liner including an annular holder having a plurality of lugs projecting outward from the outer edge thereof, each lug having an undercut end, a plurality of seg-

60 mental sections embracing the front face of the holder and having rim portions provided with slots receiving the lugs, each slot having an inclined end engaging the undercut end of the lug, and means for bolt- 60 ing the sections together on the holder.

6. A sectional journal box and hub liner including an annular holder having a peripheral rib adjacent to its front face, the rib being provided with a plurality of projecting lugs, a plurality of segmental sections together covering the front face of the holder and provided with rim portions embracing said rib, the rim portions having lips engaging the rear side of the rib and having 65 also slots receiving the lugs, and means to secure the sections together on the holder.

7. A sectional journal box and hub liner including an annular holder having a plurality of holes therein to receive securing 75 bolts, a plurality of segmental sections together covering the front face of the holder and provided with rim portions embracing the edge of the holder, each section having two ears at its ends, bolts connecting the 80 ears of each section to the ears of the companion section, and means co-operating with the holder and the sections to prevent rotation of the sections on the holder.

8. In a sectional journal box and hub liner, 85 the combination of an annular holder having a lug projecting from the outer edge thereof, a sectional liner covering the front face of the holder and provided with a lateral rim portion having a slot extending outward 90 through and receiving the lug, the sections of the liner having means securing them together.

9. In a sectional journal box and hub liner, 95 the combination of an annular holder having a plurality of lugs projecting from the outer edge thereof, and a plurality of liner sections connected together on the holder and together covering the front face of the holder, each one of the liner sections being 100 provided with a lateral rim portion having a slot extending therethrough and receiving one of said lugs.

In testimony whereof, I affix my signature in presence of two witnesses.

CHARLES N. BARTON.
